ENGINE

Arthur M. Fullerton, Toledo, Ohio, assignor to The Scott & Fetzer Company, Lakewood, Ohio, a corporation of Ohio

Filed June 13, 1968, Ser. No. 12,334

Term of patent 14 years

Int. Cl. D15—01

U.S. Cl. D77—1

FIG-5-

FIG-3-

FIG-4-

FIG. 1 is a left front view in perspective of an engine embodying my design;

FIG. 2 is a left rear view in perspective;

FIG. 3 is a front view in elevation;

FIG. 4 is a right side view in elevation;

FIG. 5 is a plan view;

FIG. 6 is a rear view in elevation;

FIG. 7 is a left side view in elevation; and

FIG. 8 is a bottom view.

The dominant parts of my design are shown in full lines.

I claim:

The ornamental design for an engine, substantially as shown and described.
